UNITED STATES PATENT OFFICE.

ALBERT B. HANCOCK, OF DUBUQUE, IOWA.

SAD-IRON.

1,108,988.

specification of Letters Patent.

Patented Sept. 1, 1914.

Application filed April 25, 1914. Serial No. 834,456.

To all whom it may concern:

Be it known that I, ALBERT B. HANCOCK, a citizen of the United States, residing at Dubuque, in the county of Dubuque and State of Iowa, have invented certain new and useful Improvements in Sad-Irons, of which the following is a specification, reference being had to the accompanying drawings.

10 This invention relates to new and useful improvements in sad-irons, and more particularly to internally heated sad-irons.

An object of this invention is the provision of a sad-iron comprising an open top body of the usual conformation of sad-irons, the body having a detachable cover connected thereto, and the cover carrying a fastening means for engagement in the body to secure the cover in a position to partially close the open top of the body.

20 A further object of this invention is the provision of a sad-iron which comprises a hollow body open at its upper end, and a detachable cover adapted to partially close the upper end of the body, the cover having upwardly projecting arms at its opposite ends upon which a handle is mounted, and the cover being provided with an insulating plate disposed between the handle and the upper face of the cover to protect the hand of the user of the iron.

25 A still further object of this invention is the provision of a sad-iron comprising a hollow body which is open at its upper end, the body carrying a grate on the bottom thereof which is adapted to support carbonaceous fuel which is to be burned within the body, the body also having draft openings formed in the sides thereof above the plane of the grate, and valve plates pivotally connected to the outer face of the body for engagement over the draft openings therein, the iron also including a detachable cover which is adapted to partially close the open upper end of the body so that a portion of the heat generated within the body is allowed to escape.

30 With these and other objects in view, my invention consists in the novel construction, combination, and arrangement of parts, to be hereinafter more fully described, claimed, and illustrated in the accompanying drawing, in which,

35 Figure 1 is a side view of a sad-iron embodying the improvements of my invention; Fig. 2 is a longitudinal vertical section

thereof; Fig. 3 is a plan view of the device; and Fig. 4 is an end view.

Referring more particularly to the drawing, the numeral 1 designates the hollow iron body which is open at its upper end, the body being of the shape of the ordinary sad iron. A grate 2 is disposed on the bottom of the body, the grate being of a shape to conform to the curvature of the body so that rattling of the grate within the iron when the same is in use, is prevented. The side walls of the body are provided with a plurality of draft openings 3 therein above the plane of the grate 2, the draft opening being preferably arranged in pairs, and pivotally connected to the body adjacent each pair of openings, is a closure or valve plate 4, the plates frictionally engaging the outer face of the body so that the same may be adjusted over the draft openings to entirely open or close the same or to partially close the openings, the plates being held in adjusted position by reason of their frictional engagement with the outer face of the body. Formed on the inner face of each side wall, adjacent one end of the body, is an inwardly extending pin 5, and a cover 6 is provided, the cover being adapted to engage the upper edges of the opposite sides of the body, and is provided at one end with a downwardly offset longitudinally projecting lug 7 which is adapted to engage below the pins 5 to secure one end of the cover to the body. The opposite end 90 of the cover 6 is also provided with a downwardly offset outwardly extending lug 8, the lug being disposed slightly below an opening 9 formed in one side wall of the body.

95 Formed on the upper face of the lug 8 is an apertured block 10, the opening in which registers with the openings 9 in the side wall of the body, and a locking rod 11 is slidably disposed in the apertured block 10 for engagement in the opening 9 to securely lock 100 the cover to the body. Formed on the opposite ends of the cover are the upstanding arms 12 which are provided at their upper ends with openings to receive a handle supporting rod 13 upon which a handle 14 is mounted between the arms 12. Pivots 105 connected intermediate of its ends to one of the arms 12, is a lever 15, the lower end of which is connected to the locking rod 11, and the upper end of which is provided 110 with a finger piece 16, whereby the lever may be operated to move the rod 11 into or

out of engagement with the opening 9 in the side of the body. Connected at its opposite ends to the handle supporting rod 13, is a bowed baffle plate 17, the intermediate portion of which extends downwardly to a point closely adjacent the upper face of the cover so that an air insulating space is formed between the opposing faces of the baffle plate and the cover.

10 In the practical use of my improved self-heating sad-iron, the desired quantity of carbonaceous fuel is disposed upon the grate 2 within the body, whereby the same is lighted, and the cover is secured to the body

15 by placing the lug 7 below the pins 5, and the opposite end of the cover is moved downwardly until the under face thereof at its opposite edges engages the upper edges of the side walls of the body, and the lug 8

20 is disposed below the opening 9 so that the opening in the block 10 registers with the opening 9 in the body. It will be seen that the lugs 7 and 8 are of a width to closely engage the inner faces of the side walls at

25 their points of engagement with the walls, so that rocking or oscillation of the cover with relation to the body is prevented. The cover is then securely locked to the body by moving the upper end of the lever 15 in the

30 the proper direction to force the locking rod 11 into engagement in the opening 9 in the body, so that separation of the cover from the body is prevented. It will be understood that the cover plates 4 may be adjusted

35 over the draft openings 3 to allow the desired amount of air to enter the body, and as the cover is relatively shorter than the length of the body, as clearly shown in the

accompanying drawing, the body is open at its opposite ends so that the heat may escape therefrom. The heat from the body is prevented from heating the handle 14 by the baffle plate 17 which is connected at its opposite ends to the handle supporting rod 13, the intermediate portion of the baffle plate 45 being disposed closely adjacent to the upper face of the cover, whereby the insulating air space is formed between the cover and the baffle plate to prevent heat from passing to the plates 17 and thence the handle.

Having thus fully described my invention, what I desire to claim and secure by Letters Patent, is:—

An internally heated sad-iron comprising a hollow body having an open top, a cover mounted on said body to partially close said open top, said cover terminating short of the ends of said body, inwardly extending pins formed on the side walls of said body adjacent one end thereof, a downwardly extending curved lug formed on one end of said cover for engagement beneath said pins, one wall of said body having an opening therein adjacent the opposite end of the body, a lever pivotally connected to said cover and carrying a locking rod for engagement through the opening in the side wall of said body, whereby to lock said cover to the body.

In testimony whereof I hereunto affix my signature in the presence of two witnesses.

ALBERT B. HANCOCK.
